UNITED STATES PATENT OFFICE.

POLYDORE GHYSSELINCK AND JOHN M. DAUWE, OF TOLEDO, OHIO.

AUTOMATIC OILER.

1,127,614.

Specification of Letters Patent.

Patented Feb. 9, 1915.

Application filed April 6, 1914. Serial No. 829,915.

To all whom it may concern:

Be it known that we, POLYDORE GHYSSELINCK and JOHN M. DAUWE, citizens of the United States, and residents of Toledo, in the county of Lucas and State of Ohio, have invented a certain new and useful Automatic Oiler; and we do hereby declare the following to be a full, clear, and exact description of the invention, such as will enable others skilled 10 in the art to which it appertains to make and use the same, reference being had to the accompanying drawings, and to the characters of reference marked thereon, which form a part of this specification.

15 Our invention relates to oilers for large bearings.

It is particularly applicable to bearings for railroad cars, engines, street cars and heavy machinery.

20 The object of our invention is to provide a means for supplying oil uniformly to bearings.

In the embodiment of our invention, the oil is preferably carried in a bearing box 25 which is located below the bearing of the shaft or axle of a wheel or wheels and the oil is conveyed from the bottom of the box or a container to the shaft or the axle as the case may be. We have shown the invention 30 as applied to a railroad car axle.

The invention may be contained in many forms of construction usable for different purposes all of which come within the purview of our claim hereinafter appended.

35 To show the practicability of our invention, we have selected one of such constructions as an example and shall describe it herein-after. The construction selected is illustrated in the accompanying drawings.

40 In the drawings, Figure 1 illustrates a sectional view of a device embodying our invention. Fig. 2 illustrates a modification of the construction shown in Fig. 1 which is particularly applicable to street car axles.

45 Fig. 3 illustrates a supporting thimble for containing one of the bearings of the oiler.

1 is the oil box for containing the oil 2. The box may be provided with a cover 3 hinged to the ears 4. The car is supported 50 indirectly upon the top 5 of the box. The bearing 6 bears against the axle 7 in the manner well known in the art. Thimbles 8 are secured by the threads 9 in the bottom of the box 1. The upper ends of the thimbles 8 are provided with slots 10. One or more wheels 11 are supported on an axle 12.

The ends of the axle extend through slots 10 located in the top of the thimbles 8 and are movable vertically in the slots. The peripheries of the wheel 11 are channeled as at 13. A tire 14 of fiber or other suitable material is molded, pressed or sprung into the periphery of the wheels 11. The material forming the rims may be greatly varied the object being to provide a slightly absorbent material or a material to which the oil will be more or less adhesive when they are rotated by the operation of the axle 7. The ends of the axle 12 are supported on a yielding bearing 15 which is provided with two upwardly extending lugs 16 located on opposite sides of each end of the axle 12. The point 17 at which the bearing 15 supports the end of the axle 12 is rounded in the plane of the axes of the bearing 15 and the axle 12 to allow vertical movement of either end of the axle 12 relative to the other bearing. The bearings are also rounded transverse the axle 12 to conform to the contour of the ends of the axle 12. The bearings 15 are yielding supported by the spring 18 located in the bottom of the thimbles 8. The axle 12 is provided with fillets 19 at the points near where it enters the thimbles 8 and the edges of the slots 10 are chamfered 20 so as to register with the fillet 19 to provide for lateral swing of the car and box. A suitable washer of copper or other soft metal 21 is located intermediate the head 22 of the thimble 8 to bring the slots 10 in 25 alignment with the axle 12 and securely lock the thimbles and form a tight fit between the thimbles 8 and the bottom of the box 1.

In the operation of the device, the wheels 11 are rotated by their pressure against the axle 7, the wheels 11 being lifted by the springs 18 against the axle 7. The lower parts of the wheel 11 are located below the surface of the oil 2 and in their rotation they carry the oil to the axle 7, which, in its 30 rotation, carries it between the bearing 6 and the axle 7. In this way the axle is constantly and uniformly oiled.

The construction selected and described may be greatly varied in the arrangement 35 and manufacture of its parts and in the substitution of elements having equivalent functions and such modifications may be used for many varied purposes and still contain the invention which is described in 40 the claim in the language of the elements shown.

What we claim as new and desire to secure by Letters Patent, is, as follows:

The combination of an axle and a bearing therefor, a box for containing the bearing and the end of the axle and oil, an oil wheel having an axle, a pair of threaded thimbles located in the bottom of the box and having slots to receive the ends of the axle of the oil wheel, the axle having fillets at its ends and the edges of the slots of the thimbles beveled to register with the fillets, the thimbles adapted to be threaded in the bottom of the box, copper washers for permitting the slots of the thimbles to be brought in alignment with the axle of the oil wheel, movable

bearings having bearing surfaces rounded in the planes passing through the axis of the oil wheel and springs located in the bottom of the thimbles for yieldingly supporting the bearings and pressing the oil wheel 20 against the first named axle.

In testimony whereof, we have hereunto signed our names to this specification in the presence of two subscribing witnesses.

POLYDORE GHYSELINCK.
JOHN M. DAUWE.
